(57) **CLAIM**

We claim the ornamental design for a bottle, as shown and described.

DESCRIPTION

FIG. 1 is a front perspective view of a bottle showing the new design;

FIG. 2 is a top plan view of the bottle of FIG. 1;

FIG. 3 is a bottom plan view of the bottle of FIG. 1;

FIG. 4 is a front elevational view of the bottle of FIG. 1;

FIG. 5 is a rear elevational view of the bottle of FIG. 1;

FIG. 6 is a left side elevation view of the bottle of FIG. 1; and,

FIG. 7 is a right side elevation view of the bottle of FIG. 1.

The evenly-dashed broken lines in the drawings illustrate the portions of the design that form no part of the claim. The dot-dot-dash broken lines in the drawings define the bounds of the claim and form no part thereof.
